UNITED STATES PATENT OFFICE.

HENRY JACQUES GAISMAN AND JOSEPH ROSS, OF NEW YORK, N. Y.; SAID ROSS ASSIGNOR TO SAID GAISMAN AND FERDINAND S. M. BLUN, OF NEW YORK, N. Y.

WAIST-BELT.

SPECIFICATION forming part of Letters Patent No. 703,568, dated July 1, 1902.

Application filed September 7, 1901. Serial No. 74,661. (No model.)

To all whom it may concern:

Be it known that we, HENRY JACQUES GAISMAN and JOSEPH ROSS, citizens of the United States, and residents of New York city, county 5 and State of New York, have invented certain new and useful Improvements in Waist-Belts, of which the following is a specification.

Our invention relates to an improved belt, strap, or the like, particularly adapted for use 10 around a person's waist; and the invention comprises an intermediate or central portion made of braided strands and end portions connected thereto, one of which end portions carries a buckle and the other is adapted to connect therewith. By preference the strands and end portions are made of tubular or folded material, whereby finished edges are provided, and the ends of the strands are located 15 in the bores of the end portions and are there concealed and fastened.

Reference is to be had to the accompanying drawings, forming part hereof, wherein—

Figure 1 is a face view of a belt embodying our invention. Fig. 2 is an enlarged detail 25 view of the reverse side thereof, partly broken. Fig. 3 is a perspective detail on the line 3 3 in Fig. 2. Fig. 4 is a cross-section, enlarged, on the line 4 4 in Fig. 1; and Fig. 5 is a side view of one end of the belt.

Similar numerals of reference indicate corresponding parts in the several views.

In the drawings the numeral 1 indicates strands, of which several are braided together, forming the main intermediate or central portion of the belt or strap, and 2 3 are the end portions, respectively secured to the opposite ends of the strands 1. To the end portion 2 is attached a suitable buckle 4, adapted to connect with the end portion 3, as by holes 3^a 35 therein, adapted to receive the tongue 4^a of the buckle. The strands 1 are preferably formed into a flat braid, and the ends of the strands are placed side by side and there secured to the end portions 2 3. To provide the strands 1 with finished or rounded edges, we make the strands in tubular form, as by folding the material of the strand upon itself, (see Fig. 4,) preferably causing the edges to abut between the marginal or outer edges of the strand, and

the folds are secured together, preferably by 50 stitching the abutting edges together, as shown at 1^a. Lines of stitches 1^b may be placed near the side edges of the strands for embellishment and to strengthen the strands. The end portions 2 and 3 are also preferably 55 made in tubular form, respectively adapted to receive in their bores the corresponding ends of the strands 1, and the tubular portions are made by folding the material upon itself, as described with reference to the strands 1, the 60 abutting edges being preferably stitched together, as shown at 3^b in Fig. 3. After the ends of the braid of strands are passed into the bores of the portions 2 3 the parts are secured together, as by stitches 5. The tip 6 of 65 the portion 3 may be finished by folding back and stitching the outer end. The tubular end portion 2 is looped through the buckle, folded upon itself, and secured together, as by stitches, and a loop 7 for the end of the 70 portion 3 may be secured in the fold of the portion 2 behind the buckle, all as in Fig. 5.

The parts 1, 2, 3, and 4 forming the belt or strap will be strong, durable, and attractive, and as the parts 1, 2, and 3 have folded or 75 rounded edges a very serviceable and neat article is produced, raw edges being avoided, and the salability of this class of belt is enhanced.

Having now described our invention, what 80 we claim is—

1. A belt, strap or the like comprising strands braided together, the material of the strands being folded upon itself in a longitudinal direction so that the edges face each 85 other, end portions secured to said strands, and means for attaching the end portions together, substantially as described.

2. A belt, strap or the like comprising strands braided together, the material of the 90 strands being folded upon itself in a longitudinal direction and the longitudinal edges secured together, end portions comprising material forming a space in which the ends of the strands are located and secured, and means 95 for attaching the end portions together, substantially as described.

3. A belt, strap or the like comprising

strands braided together, the material of the strands being folded in a longitudinal direction upon itself providing rounded edges, the abutting edges of the material being secured together, end portions composed of material folded in a longitudinal direction and its edges secured together forming bores in which the ends of the strands are located and se- cured, and a buckle secured to one of the end portions, substantially as described.

HENRY JACQUES GAISMAN.
